UNITED STATES PATENT OFFICE.

WILLIAM J. ROCHE AND HOWARD L. MOORE, OF COCHRANTON, PENNSYLVANIA.

EXERCISING DEVICE.

Application filed March 5, 1926. Serial No. 92,485.

This invention relates to an improved exercising device, which has been perfected with the object of widening the scope and varying the character of the exercises which may be performed with its assistance.

More specifically stated, the objects of the invention include the provision of an exercising device which may be used with or without stirrups, in standing or sitting position, to exercise the chest, back or leg muscles. By sitting on the floor, and using the device in connection with the stirrups, a true rowing motion may be obtained, exercising all the muscles of the body and reducing abdominal fat.

The specific construction of the invention and the manner in which it may be used will be more fully explained in connection with the accompanying drawing, which illustrates one embodiment thereof.

In the drawing:

Figure 1 is a plan view of the invention with the stirrups attached.

Figure 2 is a similar view of the invention as used without the stirrups.

Figure 3 is a detail sectional view of one of the handles.

Figure 4 is a detail sectional view of the roller and the bracket in which the same is mounted.

Referring in detail to the drawing, the invention comprises a bracket 5, of cast metal or other suitable material, and provided with opposed ears 6 and 7, having aligned openings to receive a threaded spindle or bolt 8, which is retained therein by means of a wing nut 9 or the like. A roller 10 of hard wood, or equivalent material, is mounted on the spindle 8, and is provided with circumferential corrugations or grooves 11 for receiving and guiding elastic cords 12. These cords are provided at their ends with hooks 13, or similar means for connecting them to heads 14. A yoke 15 is swiveled, as at 16, to each head 14, and carries a handle 17.

The bracket 5 is provided centrally with an eye 18, adapted to receive a snap hook 19, which is connected by chains 20 to stirrups 21, or the eye 18 may be connected with a hook 22 secured to the wall of the room. All of the metallic parts of the exerciser are preferably nickel plated, and the other parts are finished in such a manner as to present an attractive appearance.

The exercising device, with the stirrups connected thereto, is used by sitting on the floor, placing the feet in the stirrups, and grasping the handles 17. The strength of the arms is then pitted against the resistance of the feet in the stirrups, and a regular rowing motion can be simulated, which is especially beneficial for massaging the stomach muscles, as well as the back muscles, and in removing abdominal fat.

After going through with the sitting exercises, the device can be disconnected from the snap hook 19 and used as a chest developer, moving the arms back and forth while stretching the elastic cords 12. In this exercise, the roller 10 and bracket 5 may be allowed to ride on the elastic cords, since their weight is very little, and will offer practically no interference in chest exercising. If desired, however, the bracket and roller may be removed merely by taking off the wing nut 9.

Another important feature of the exerciser is that when the stirrups are disconnected from the bracket 5, the latter may be connected to the hook 22, secured in the side wall or door frame about the height of the shoulders. Then, a person with back to the hook 22 may perform valuable arm exercises, shoving the arms straight out or sideways, which develops the muscles of the shoulders, as well as those of the arms.

From the foregoing description, it will be seen that we have provided an exercising device which may be used in a great variety of ways with the operator either sitting or standing. Practically all of the muscles in the legs, arms, back, chest and abdomen may be exercised in the most efficient manner. While we have shown and described specifically the details of construction representing one form in which the invention may be embodied, it is to be understood that various modifications may be made in the form and relation of the various parts thereof without any material departure from the salient features of the invention as expressed in the claims.

What is claimed is:

1. In an exercising device, the combination of a bracket, a guide member supported thereby, a flexible elastic member passing about said guide member and provided at each end with a handle, the ends of said elastic members being otherwise free so

that they may be moved independently in any direction, a pair of flexible members, each connected at one end to said bracket with its other end free, and a stirrup connected to each of said free ends.

2. In an exercising device, the combination of a bracket, a detachable guide member carried thereby, a flexible elastic member passing about said guide member with each end provided with a handle but otherwise free, a pair of flexible members, each connected at one end to said bracket with its other end free, and a pair of stirrups connected respectively to the free ends of the last-mentioned flexible members, whereby the handles and elastic member may be used in connection with the guide member, bracket and stirrups, or may be used alone upon freeing the same from the guide member by the detachment of the latter from the bracket.

3. In an exercising device, the combination of a bracket having a pair of ears with aligned openings therein, a spindle removably mounted in said openings, a roller adapted to be mounted on the spindle and having circumferential grooves, elastic cords adapted to be guided over the roller in said grooves, handles connected respectively to the ends of the several cords, a pair of flexible members, each connected at one end to said bracket with its other end free, and a pair of stirrups connected to the respective free ends.

4. In an exercising device, the combination of a bracket having a pair of ears with a spindle removably mounted in said ears, a roller adapted to be mounted on the spindle and having circumferential grooves, elastic cords adapted to be guided over the roller in said grooves, handles connected respectively to the ends of the several cords, said bracket having an eye located centrally of its rear side, and a pair of stirrups with flexible members connected thereto and de-

tachably connected with said eye, whereby the device may be used with the bracket free, or connected to the stirrups, or connected to a stationary hook, or the handles and elastic cords may be used alone upon 50 freeing the same from the roller by the detachment of the spindle from the bracket.

5. In an exercising device, the combination of a pair of handles, a head swiveled to each handle, a plurality of elastic cords connecting the two heads, a bracket having a pair of spaced ears, a spindle removably mounted in said ears, a roller adapted to be mounted on the spindle and having circumferential grooves in which said cords may be guided over the roller, a pair of flexible members, each connected at one end to said bracket with its other end free, and a pair of stirrups connected to the respective free ends.

6. In an exercising device, the combination of a pair of handles, a head swiveled to each handle, a plurality of elastic cords connecting the two heads, a bracket having a pair of spaced ears, a spindle removably mounted in said ears, a roller adapted to be mounted on the spindle and having circumferential grooves in which said cords may be guided over the roller, said bracket having an eye located centrally of its rear side, 75 and a pair of stirrups with flexible members connected thereto and detachably connected with said eye, whereby the device may be used with the bracket free, or connected to the stirrups, or connected to a stationary hook, or the handles and elastic cords may be used alone upon 80 freeing the same from the roller by the detachment of the spindle from the bracket.

In testimony that we claim the foregoing as our own, we have hereto affixed our signatures.

WILLIAM J. ROCHE.
HOWARD L. MOORE.
